Specification for Design.

Patented July 5, 1910.

Application filed May 12, 1910. Serial No. 561,020. Term of patent 14 years.

To all whom it may concern:

Be it known that I, EDWIN L. THOMAS, a citizen of the United States, residing at Buffalo, in the county of Erie and State of New York, have invented a new, original, and ornamental Design for Automobile-Bodies, of which the following is a specification, reference being had to the accompanying drawings, forming part thereof.

Figure 1 is a perspective view from the front of an automobile body showing my

new design. Fig. 2 is a similar view from the rear of an automobile body showing my new design.

I claim:

The ornamental design for an automobile body, as shown.

EDWIN L. THOMAS.
